UNITED STATES PATENT OFFICE.

ALBERT C. MURPHY, OF NEW YORK, N. Y.

DUMPING-CAR.

1,189,283.

Specification of Letters Patent.

Patented July 4, 1916.

Application filed October 17, 1914. Serial No. 867,058.

To all whom it may concern:

Be it known that I, ALBERT C. MURPHY, a citizen of the United States, and resident of New York, county of New York, and State of New York, have invented an Improvement in Dumping-Cars, of which the following is a specification.

My invention has for its object the construction of a dumping car which may be 10 preferably operated from both ends of the car, whereby the body may be rocked upon its bed to dump to either side of the car, my present improvements providing automatic side doors for the body and guiding means 15 for guiding the contents a distance from the road bed when the body has been tilted into discharging position.

My object is also to provide a dumping car of the general character above specified in which the automatic mechanism may 20 be thrown out of action, and in which, further, a plurality of the doors upon the sides of the body may be manually controlled so that only certain doors will open for discharging the contents of the body when 25 tilted into discharging position.

My invention consists of constructions in a dumping car which are fully described hereinafter and more particularly defined 30 in the claims, and these will be better understood by reference to the drawings, in which:—

Figure 1 is a plan view of a car embodying my improvements; Fig. 2 is a side elevation of one end of the car with portions broken away; Fig. 3 is a transverse sectional elevation of my improved car taken on line $x-x$ of Fig. 2; Fig. 4 is a cross sectional view of one of the latches for the 40 doors; Fig. 5 is an elevation showing the means for throwing the automatic mechanism for releasing the doors into or out of action; Fig. 6 is a sectional elevation of one of the adjustable links for controlling 45 the chute plates; Fig. 7 is a transverse section on line $y-y$ of Fig. 5; and Fig. 8 is a transverse sectional view illustrating a modified arrangement of the doors.

2 is the longitudinal main frame and has 50 at its respective ends platforms 2^a and 2^b , in which the means for tilting the body are arranged.

6 represents the dumping body of the car and is provided with rockers 7 on its

under part, which rock upon rocker beds 4 55 arranged transversely of the longitudinal main frame 2, said construction providing for rocking of the body to either side of the main frame whereby the car has capacity for dumping to each side of the track. The 60 body is rocked by means of the racks 30 which are reciprocated vertically by pinions 32 rotating with longitudinal shafts 31 journaled in bearings in the brackets 3 forming a part of the main frame 2, extending the whole length of the car and to the platforms at each end. These longitudinal shafts 31 are provided with sprocket 65 wheels 33 below the platforms and said sprocket wheels are rotated by sprocket 70 chains 34 operated by suitable hand power devices 35 arranged within cabs on the platforms. As shown, one of the shafts 31 may be operated from one platform and the other shaft operated from the other platform, and the manipulation of either shaft will produce a rocking motion to the body. 75 I do not restrict myself in any manner as to the means employed for rocking the body, and in respect to the particular means 80 here shown said means is fully set out and claimed in my application Serial No. 848,728, filed July 3, 1914.

The body 6 may be constructed in any suitable manner and suitably braced, but 85 has its sides provided with openings through which the contents may be dumped, and these side openings are normally closed by hinged doors 9 preferably hinged at the upper ends at 10 upon a longitudinal girder 90 8 forming the upper boundary of the body. The lower portions of these doors are provided with keepers which are engaged by the latches 11, said latches having capacity for both automatic and hand operation. The 95 automatic feature of these latches is such that when the body is tilted approximately into dumping position the latches release the doors so that the contents can only be discharged when the body has assumed the 100 proper position for such discharge. I, however, do not restrict myself as to the particular time of unlatching the doors. These latches 11 are journaled upon a rock shaft 12 and may have spring actuated friction devices 29 so that the latches are frictionally supported to move with the shafts 12 and also to hold themselves in raised or releas-

ing position upon the shaft 12 when moved into that position by hand manipulation. (See dotted line at right hand part of Fig. 3).

5 Extending through the rock shaft 12 in line with the hub of each of the latches 11 is a bolt 25 having a head 26 at one end and a nut 27 at the other end, and said head and nut are arranged in slotted portions 28 in 10 the hub of the latch. By referring to Fig. 4 it will be seen that the latch 11 may be raised by hand without disturbing the rock shaft 12 and its bolt, said movement permitting a release of the doors 9 when desired without 15 operating the rock shaft. It will, however, be observed that the rock shaft 12 is rocked in the reverse direction to the hands of a watch; the head 26 and the nut 27 acting against the wall of the slot 28 will rock the 20 latch to a releasing position. By my improvements this rock shaft 12 is adapted to be rocked automatically in the act of tilting the body, or may remain inactive by hand adjustment in a manner to be later described. 25 Pivoted upon the rock shaft 12 are a plurality of arms 13 which may be provided with a sheet metal plate 14 to constitute a guiding or chute plate. This chute plate 14 and its arms 13 normally hang substantially 30 vertically, but when the body is tilted to the dotted position shown in Fig. 3 said chute plate is also tilted into an oblique position as indicated in dotted lines so as to receive and guide the contents on its leaving the body, 35 said chute plate causing the load to be discharged to a distance from the side of the track. The means for causing the tilting of the chute plate 14 and its arms 13 into the oblique position consists of the strut 15 and 40 the slotted abutment frame 19 which is secured to the lower part of the longitudinal main frame and braced by the struts 20. The struts 15 are of the construction illustrated in Fig. 6 and comprise a tubular member 16 45 in which is arranged a plunger 17, the former being pivoted to the arms 13 of the chute plate and the latter provided with a transverse pin which works in the slotted guideways of the frame 19. This extensible 50 strut in the normal position of the car body is partly extended as clearly shown in Figs. 2 and 3, but when the car body is tilted into the dotted position the said members 16 and 17 will be collapsed, and in that event the 55 strut 15 so holds the arms and the chute plates that the rocking of the body positively shifts them and their rock shaft support as to make them assume the inclined position shown in dotted lines in Fig. 3. While this 60 operation is taking place at the side of the body which is lowered, there is another operation upon the chute plates and latches at the opposite side, namely, that which is rising, but in this case the strut will not only 65 have its telescopic members expanded as

shown in dotted lines but the cross pin 18 will have been drawn upward to the highest end of the slot in the slotted guide frame 19, these adjustments permitting the maintenance of the proper connections between the chute plates and the guides so that the strut may properly operate in the manner first described when the body is tilted downward in the act of dumping the load.

The shafts 12 for operating the latches 11 75 and for supporting the chute plate and frame structures 14 and 13 are respectively journaled at each side of the body immediately below the bottom at the outer side edges. These shafts 12 may be allowed to 80 remain stationary and permit the latches 11 to be operated by hand as hereinbefore described in releasing or latching the side doors 9 wholly or in part, all being latched as when the car is to be loaded, and one or 85 more of the doors unlatched when it is desired to dump only a portion of the load. However, when the latches are to be operated automatically so that all of the doors are released this result is accomplished more 90 particularly by the mechanism shown in Figs. 5 and 7. As the mechanism at each side of the car is the same in construction it will suffice to describe the construction on 95 one side of the car.

Sliding upon the shaft 12 is a sleeve 21, said sleeve being caused to rotate or rock with the shaft by reason of the presence of the spline 24. This sleeve 21 is provided with teeth 22 upon its end and it is further 100 provided with the spring 25 which engages notches 26 to hold the sleeve out of or into engagement with the lugs or teeth 23 on one of the frames or arms 13 which is rocked as a part of the chute plate. The space 23a 105 between the lugs 23 is such that the lugs 22 are not acted upon to lock the shaft 12 until the arm 13 and the chute plate carried thereby is raised almost to the inclined position which it must assume when the load is to be discharged. After this preliminary movement the further movement of the arm 13 will operate to cause the teeth 23 to engage the teeth 22 and rotate the sleeve 21 and the shaft 12 a few degrees, namely, sufficient to lift the latch 11 to release the doors, whereupon the load pressing against the doors forces them open and is automatically discharged over the inclined chute plates. In the preferred construction I provide that the chute plate arm 13 shall move through an angle of 72 degrees during the tilting of the body before the latches begin their releasing motion and that the latches shall be fully released during a further movement of approximately 18 degrees, these movements being indicated diagrammatically in Fig. 7. Upon the return movement due to the righting of the body the teeth 23 will move away from the teeth 22. 115 120 125 130

and may travel approximately through 72 degrees before again operating the shaft 12 in returning it to its original normal position. In other words, the teeth 23 play between the teeth 22 so that they operate upon the latter both in lifting the latches and when re-setting the shaft and latches to their original positions. When it is desired that the latches shall not be operated automatically the sleeve 21 is adjusted to the position shown in Fig. 5, but when it is required that it shall be automatically operated then the sleeve 21 is moved to the right so that the teeth 22 will be received in the space 23^a between the teeth 23. When the body is righted to a horizontal position and the doors 9 close, the latches 11 are pushed down by hand to the positions indicated in Figs. 3 and 4 to engage and hold the doors in closed position.

While I have shown a specific means for putting the rock shafts 12 into and out of automatic operation it is to be understood that I do not restrict myself to any particular means for accomplishing this purpose, for instead of the teeth 23 being operated by the arm 13 of the chute plates 14 these teeth may be operated by any other suitable mechanism put into action by the tilting of the body into a dumping position, the construction here shown being by way of example only.

While I prefer that the doors 9 shall be hinged at the top and latched at the bottom, this is not essential to the invention broadly as will be evident from reference to Fig. 8. In this case the latches 11^a are shown at the upper part of the body whereas the doors 14^a are indicated as hinged to the same shaft 12 to which the arms 13 are hinged. In this case the doors 14^a will act as chute plates for the load and therefore they may rest directly against the arms 13 and supplement or take the place of the chute plates 14 shown in Fig. 3. The latches 11^a may be carried upon a shaft 12^a to which they are connected as indicated in Fig. 4, and this rock shaft 12^a may be rocked from the rock shaft 12 by connections 12^b or of any other suitable means.

While I have shown the guides 19 as slotted plates or frames it is to be understood that I do not restrict myself in this respect as the guiding union between the abutment struts 15 and the main frame of the car may be made in any suitable manner capable of performing the functions or operations herein defined.

While I have shown my improvements as applied to a dumping car in the preferred form, I do not restrict myself to the details as these may be modified in any suitable manner without departing from the spirit of the invention.

Having now described my invention,

what I claim and desire to protect by Letters Patent of the United States is:—

1. In a dumping car, the combination of the main frame, a body supported upon the main frame and adapted to be oscillated to discharge to either side thereof said body having discharge openings on its sides, doors hinged to the body at the upper edges of its side discharge openings, chute plates hinged to the lower side edges of the body, latches for holding the doors in closed position, means for moving the chute plates in an oblique position when the body is tilted to discharge its contents, and power devices for tilting the body.

2. In a dumping car, the combination of the main frame, a body supported upon the main frame and adapted to be oscillated to discharge to either side thereof said body having discharge openings on its sides, doors hinged to the body at the upper edges of its side discharge openings, chute plates hinged to the lower side edges of the body, latches for holding the doors in closed position, means for moving the chute plates in an oblique position when the body is tilted to discharge its contents, automatic devices for operating the latches to release the doors when the body is tilted and the chute plates moved to an inclined position, and power devices for tilting the body.

3. In a dumping car, the combination of the main frame, a body supported upon the main frame and adapted to be oscillated to discharge to either side thereof, said body having discharge openings on its sides, doors hinged to the body at the upper edges of its side discharge openings, chute plates hinged to the lower side edges of the body, latches for holding the doors in closed position, means for moving the chute plates in an oblique position when the body is tilted to discharge its contents, automatic devices for operating the latches to release the doors when the body is tilted and the chute plates moved to an inclined position, hand controlled means for putting the latches into or out of automatic relation with the chute plate operating means for converting them into automatic or manually operated latches as required, and power devices for tilting the body.

4. In a dumping car, the combination of a longitudinal frame, a body supported upon the longitudinal frame and adapted to tilt for dumping its load, a door hinged to the upper part of the body to close the side opening thereof, a latch at the lower part of the body for engaging the door, a chute plate hinged to the lower part of the body adjacent to its side, means for moving the chute plate into an oblique position when the body is tilted into dumping position, automatic means controlled by the movement of the chute and its operating mechanism.

for actuating the latch for automatically releasing the door when the body is brought into dumping position, and power devices for tilting the body.

- 5 5. In a dumping car, the combination of a longitudinal frame, a body supported upon the longitudinal frame and adapted to tilt for dumping its load, a door hinged to the upper part of the body to close the side opening thereof, a latch at the lower part of the body for engaging the door, a chute plate hinged to the lower part of the body adjacent to its side, means for moving the chute plate into an oblique position when the body is tilted into dumping position, automatic means controlled by the movement of the chute and its operating mechanism for actuating the latch for automatically releasing the door when the body is brought into dumping position, means for throwing the latch out of automatic connection whereby it becomes a manually operated latch when desired, and power devices for tilting the body.
- 10 6. In a dumping car, the main frame, a body supported by the main frame and adapted to tilt for dumping to either side of the track, a pivoted chute plate structure at each side of the body and by which the contents may be guided when being discharged, power devices for tilting the body, and means for automatically moving the respective chute plates into oblique guiding position when the side of the body to which they are arranged is lowered for dumping, said means consisting of a guide carried by the main frame and having a general direction from a higher to a lower plane, and extensible connections one of the ends of which are hinged to the respective adjustable chute plate structures and the other ends guided in the guides whereby one of the extensible connections acts as a strut when the chute plate structure is lowered at one side of the car and the other extensible connection at the other side of the car is extended and guided upward upon its guide to compensate for the changed elevation of its guide chute structure.
- 15 7. In a dumping car, the combination of the main frame, a car body supported thereon and adapted to be tilted for dumping its contents, said body having a side opening and a longitudinal upper frame, a door hinged to the upper frame and swinging outwardly at the bottom, power devices for tilting the body, a plate hinged to the body at its lower part and immediately under the lower end of the door when closed and acting to guide the contents when being discharged, and means acting as a strut to support the plate in an inclined position when the body is moved into dumping position.
- 20 8. In a dumping car, the combination of the main frame, a car body supported there-

on and adapted to be tilted for dumping its contents, power devices for tilting the body, a plate hinged to the body at its lower part and acting to guide the contents when being discharged, and extensible means acting as a strut to support the plate in an inclined position when the body is moved into dumping position, and a guide carried upon the main frame and having an upward direction and in which the extensible means is guided.

9. In a dumping car, the combination of a main frame, a body supported upon the main frame and adapted to be tilted for dumping its contents, means for tilting the body, means for controlling the discharge of the contents from the body and guiding it away from the car in the act of its discharge, said means comprising a door hinged to the side of the body at a distance above the side edge of the floor and a plate hinged at the under side of the side edge of the floor and immediately below the door when closed and connecting means between the main frame and the means releasing the door and moving the plate for controlling the discharge of the contents from the body automatically when the body is tilted.

10. In a dumping car, the combination of a main frame, a car body supported thereon and adapted to be tilted for discharging its contents, power devices for tilting the body, a plate hinged to the side of the body and adapted to act as a chute when the body is tilted into discharging position, and means to move the said chute plate into an oblique position when the body is tilted and into a substantially vertical position when the body is in a normal horizontal position, said means comprising a telescopic strut one end of which is connected with the main frame and the other end with the chute plate.

11. In a dumping car, the combination of a main frame, a car body supported thereon and adapted to be tilted for discharging its contents, power devices for tilting the body, a plate hinged to the side of the body and adapted to act as a chute when the body is tilted into discharging position, and means to move the said chute plate into an oblique position when the body is tilted and into a substantially vertical position when the body is in a normal horizontal position, said means comprising an extensible connection between the hinged guide plate and the main frame formed of three parts slidably connected.

12. In a dumping car, the combination of a main frame, a car body supported thereon and adapted to be tilted for discharging its contents, power devices for tilting the body, a plate hinged to the side of the body and adapted to act as a chute when the body is tilted into discharging position, means to move the said chute plate into an oblique position when the body is tilted and into a

substantially vertical position when the body is in a normal horizontal position, said means comprising a slotted guide-way on the main frame, and an extensible connection between the chute plate and the slot of the guide-way and which acts as a strut when fully lowered and is extensible and guided in the guide-way when fully raised.

13. In a dumping car, the combination of a main frame, a body adapted to be oscillated thereon, a pivoted door at the side of the body to control the discharge of its contents, a latch for locking the door in closed position, automatic mechanism for automatically operating the latch for releasing the door when the body is tilted into dumping position, and hand controlled means for throwing the automatic mechanism into or out of action.

14. In a dumping car, the combination of a main frame, a body supported thereon and adapted to tilt for dumping the contents therefrom, a door hinged to the side of the body, a rock shaft, a latch frictionally carried with the rock shaft so as to be manually operated thereon for latching or releasing the door, automatic means for rocking the rock shaft when the body is tilted into dumping position, and hand controlled means for throwing the rock shaft into or

out of operative automatic relation whereby the latch may be wholly manually operated or may be automatically operated as desired.

15. In a dumping car, the combination of a main frame, a body supported thereon and adapted to be oscillated for dumping its contents, power devices to oscillate the body, a plurality of doors to control the discharge of different portions of the contents of the body, a plurality of latches to control the respective doors, a shaft common to all of the latches and upon which they have a limited play under hand manipulation but all of which latches may be simultaneously operated by the rocking of the shaft, automatic means for rocking said shaft when the body is tilted into dumping position, and hand controlled means for throwing the shaft out of engagement with the automatic means whereby any of the doors may be manually unlatched and the remaining doors remain latched during the tilting of the body, or whereby all of the doors may be automatically unlatched as desired.

In testimony of which invention, I hereunto set my hand.

ALBERT C. MURPHY.
